HOIST

Charles F. Osgood, Franklin, Pa., assignor to
Joy Manufacturing Company, a corporation of
Pennsylvania

Application December 6, 1945, Serial No. 633,063

13 Claims. (Cl. 254—185)

1

This invention relates to hoists and more particularly to improvements in a double drum scraper hoist especially designed for use in mines.

An object of the present invention is to provide an improved hoist. Another object is to provide an improved hoist having improved mounting means for the cable winding drums and improved driving means for the drums. A further object is to provide an improved double drum hoist having relatively rotatable cable winding drums provided with frictionally controlled planetary driving means whereby the drums may be independently driven. A still further object is to provide an improved drive shaft arrangement for a hoist wherein the cable winding drums are journaled on and supported by the drive shafts. Yet another object is to provide an improved double drum hoist having improved driving and controlling means for the cable winding drums whereby the latter may be driven and controlled in an improved manner. Still another object is to provide an improved hoist of the double drum type having improved supporting and driving means for the drums whereby the latter may be easily assembled and may be readily dismantled. A still further object is to provide an improved double drum hoist which may be easily transformed into a single drum hoist with relatively small change. A still further object is to provide an improved releasable coupling means between the aligned drive shafts of a hoist of the above character. These and other objects and advantages of the invention will, however, hereinafter more fully appear.

In the accompanying drawings there are shown for purposes of illustration several forms and modifications which the invention may assume in practice.

In these drawings:

Fig. 1 is a view in central longitudinal vertical section taken through a hoist constructed in accordance with an illustrative embodiment of the invention.

Fig. 2 is a fragmentary sectional view taken on the plane of Fig. 1, showing a modified construction.

Fig. 3 is a cross-sectional view taken on line 3—3 of Fig. 1.

Fig. 4 is a cross-sectional view taken on line 4—4 of Fig. 1.

Fig. 5 is a perspective view showing details of the coupling.

Fig. 6 is a side elevational view, on a reduced scale, showing the hoist of Fig. 1 transformed into a single drum hoist.

2

Fig. 7 is a sectional view similar to Fig. 1, showing another embodiment of the invention.

Fig. 8 is a fragmentary sectional view taken on the plane of Fig. 7, showing a further modified construction.

In the illustrative embodiment of the invention shown in Figs. 1, 3, 4 and 5, the hoist is generally designated 1 and comprises a base frame 2 carrying upstanding end supports 3 and 4 and an intermediate central support 5. Axially aligned shafts 6 and 7 are journaled within the end and central supports in the manner shown, and arranged between the end supports and the central support at opposite sides of the latter and journaled on and supported wholly by the aligned shafts respectively are relatively rotatable cable winding drums 8 and 9. The shafts 6, 7 respectively support spaced bearings 10 and 11 on which the drums are journaled for rotation relative to the shafts, and the central support 5 carries spaced bearings 12, 12 in which the adjacent ends of the aligned shafts 6 and 7 are respectively journaled. The aligned shafts are suitably coupled together and herein arranged in the central support 5 intermediate the bearings 12 is an internally toothed coupling ring 13, the teeth of which are interlocked with teeth of reduced end portions 14 of the shafts. The coupling is designed so that the shafts may be out of exact alignment while connected for rotation together and so that the shafts may be separated axially simply by sliding the shaft teeth out of the coupling ring 13. The inner ends of the drums have circular peripheral flanges 15 which are received in annular recesses 16 extending about the periphery of the circular portion of the central support 5, to seal out dirt from the internal mechanism. A motor 17 carried by a projection 18 integral with the base frame at one end of the latter has a gear 19 keyed to its power shaft and meshing with an internal gear 20 keyed to the adjacent end of the shaft 6. Keyed to the remote ends of the axially aligned shafts 6 and 7 near the end supports 3 and 4 are spur gears 21 and 22 which respectively mesh with planet gears 23 journaled on shafts 24 secured to the drums in parallelism with the axially aligned shafts. The planet gears mesh with internal gears 25 respectively formed on rotatable reaction members 26 and 27 which have their rotation controlled by conventional brake bands 28. The hubs 29 of the reaction members are journaled in bearings 30, 30 carried by the end supports, and the hubs 29 carry spaced bearings 31, 31 in which the remote ends of the axially aligned shafts 6 and 7

are journaled. The brake bands 28 have suitable toggle-like operating means 32 whereby the brakes may be independently applied to control the reaction members 26 and 27. Thus when the reaction members are held against rotation by the brake bands, the cable winding drums may be driven in cable winding direction through the gears 19, 20, shaft 6, coupling 13, 14, shaft 1, gears 21, 22, planet gears 23 and internal gears 25, and by slipping the brake bands, the driving speeds may be varied as desired. The adjacent ends of the drums are engaged by conventional brake bands 33 operated through suitable linkage 34 to brake drum rotation as desired.

In the modification shown in Fig. 2, the central support 5' is made relatively narrow so that the drums may be placed closer together and the adjacent ends of the drums have projecting circular flanges 35 received in annular grooves 36 in the opposite sides of the central support to seal out dirt. The bearings 12 for the adjacent ends of the axially alined shafts 6 and 7 are supported within an enlarged central boss 37 on the central support and this boss extends within the drums in the manner shown. Thus not only is a more compact structure attained, but also an extremely effective dirt seal is provided between the drums and the central support.

From the foregoing, it is evident that the cable winding drums 8 and 9 are supported by and journaled in an improved manner on the end supports 3, 4 and the central support 5, and the drive shafting 6, 7 on which the drums are journaled is not only supported at its ends but also near its center. By removing the outer end support 4 from the base frame, the right-hand drum unit, as viewed in Fig. 1, may be detached from the rest of the hoist, and the shaft 7 of the right-hand drum unit when moved outwardly is readily released from the coupling ring 13 without disturbing the latter. As shown in Fig. 6, by a slight modification of the base to make the latter shorter and the provision of a detachable end cap 38 for the outer side of the then end support 5, the hoist may be readily transformed into a single drum hoist. Also by enabling such manner of detachment of the right-hand drum unit, assembly or dismantling of the hoist is facilitated.

In the modified embodiment shown in Fig. 7, the end and central supports for the axially alined drum drive shafts, and the releasable coupling between the axially alined shafts may be similar to those of Fig. 1. In this construction however, spur drive gears 21' and 22' are keyed to the alined shafts 6 and 7 near the central support 5' and mesh with planet gears 23' journaled on shafts 24' at the adjacent ends of the drums. The planet gears mesh with internal gears 25' formed on reaction members 40 and 41 controlled by brake bands 28'. The hubs 42 of the reaction members are journaled in bearings 43 supported within the central support, and the hubs 42 carry bearings 12' in which the adjacent ends of the alined shafts are journaled. Brake bands 33' are arranged at the remote ends of the drums near the end supports for braking drum rotation.

In the modification shown in Fig. 8, the central support 5'' has circular bosses 44 projecting from its opposite sides and supporting therein the bearings in which the adjacent ends of the axially alined shafts 6 and 7 are journaled. Supported by these circular bosses 44 externally thereof are bearings 43' on which the hubs 45 of the reaction members 40' and 41' are journaled. By

such an arrangement, the shafts 6 and 7 and the reaction members may be independently journaled on the central support. As in the embodiment shown in Fig. 1, the right-hand drum unit 5 may be readily detached from the hoist simply by removing the right-hand end support from the base frame and moving the shaft 7 axially with respect to the coupling ring 13.

In the several embodiments and modifications 10 above described, the motor 17 drives the axially alined shafts which carry the cable winding drums and the shafts are releasably coupled for rotation together. When the reaction members 15 are held against rotation by the brake bands, the drums may be driven through the spur gears on the shafts, the planet gears and the internal gears on the reaction members, and by slipping the brake bands which control rotation of the reaction members, the driving speeds may be varied 20 at will. The drum shafts are not only journaled in the upstanding end supports but also in the upstanding central support arranged between the drums, thereby resulting in a more stable structure. By the provision of the releasable coupling 25 between the alined shafts, one drum unit may be readily detached from the hoist without disturbing the mounting for the other drum. The reaction members which control drum rotation are journaled in certain of the upstanding supports 30 on the base frame independently of the axially alined drive shafts which support the drums. The manners of use and other advantages of the improved hoist will be clearly apparent to those skilled in the art.

While there are in this application specifically described several forms and modifications thereof which the invention may assume in practice, it will be understood that these embodiments and modifications of the same are shown for purposes of illustration and that the invention may be further modified and embodied in various other forms without departing from its spirit or the scope of the appended claims.

What I claim as new and desire to secure by Letters Patent is:

1. In a hoist, a frame having end supports and a central support, a motor carried by said frame at one end thereof, shafts driven by said motor and arranged in axial alinement and journaled at their remote ends in said end supports and at their adjacent ends in said central support, a releasable coupling arranged in said central support for connecting said axially alined shafts together, relatively rotatable cable winding drums arranged between said end supports and said central support at the opposite sides of the latter and journaled on and supported by said axially alined shafts respectively, and driving connections between said shafts respectively and said drums for independently rotating the latter in cable winding direction, said releasable coupling permitting removal of one drum, its shaft and driving connections without disturbing the central support or the other drum, its shaft and driving connections and while the shaft of said other drum remains journaled in said central support.

2. In a hoist, a frame having end supports and a central support, a motor carried by said frame at one end thereof, shafts driven by said motor and arranged in axial alinement and journaled at their remote ends in said end supports and at their adjacent ends in said central support, spaced bearings supported in said central support and

in which the adjacent ends of said shafts are journaled, a detachable coupling in said central support intermediate said bearings for connecting said shafts together, relatively rotatable cable winding drums arranged between said end supports and said central support at the opposite sides of the latter and journaled on and supported by said axially alined shafts respectively, and driving connections between said shafts respectively and said drums for independently rotating the latter in cable winding direction, said detachable coupling permitting removal of one drum, its shaft and driving connections without disturbing the central support or the other drum, its shaft and driving connections and while the shaft of said other drum remains supported within its bearing in said central support.

3. In a hoist, a frame having end supports and a central support, shafting journaled in said supports, relatively rotatable cable winding drums arranged between said end supports and said central support at the opposite sides of the latter and journaled on and supported by said shafting, and driving connections between said shafting and said drums respectively for independently rotating the latter in cable winding direction, said connections including planetary gearings one individual to each drum and each gearing including a brake controlled reaction gear, said reaction gears being arranged in adjacency to said central support and each having a hollow hub surrounding said shafting and journaled in said central support said shafting supported at intermediate points by said central support through said gear-hubs.

4. In a hoist, a frame having end supports and a central support, shafting journaled in said supports, relatively rotatable cable winding drums arranged between said end supports and said central support at the opposite sides of the latter and journaled on and supported by said shafting, and driving connections between said shafting and said drums respectively for independently rotating the latter in cable winding direction, said connections including planetary gearings one individual to each drum and each gearing including a brake controlled reaction gear, said reaction gears being arranged in adjacency to said central support and each having a hollow hub journaled in said central support and said hubs supporting bearings in which the central portion of said shafting is journaled said shafting supported at intermediate points by said central support through said gear-hubs.

5. In a hoist, a frame having end supports and a central support, a motor carried by said frame at one end thereof, shafts driven by said motor and arranged in axial alinement and journaled at their remote ends in said end supports and at their adjacent ends in said central support, the adjacent ends of said shafts having toothed portions, a toothed ring arranged in said central support and having interlocking engagement with said toothed shaft portions for coupling said shafts together, relatively rotatable cable winding drums arranged between said end supports and said central support at the opposite sides of the latter and journaled on and supported by said axially alined shafts, and driving connections between said shafts respectively and said drums for independently rotating the latter in cable winding direction, the toothed portion of one shaft being disconnectible from said toothed ring to permit removal of one drum, its shaft and driving connections without disturbing the

central support or the other drum, its shaft and driving connections and while the toothed portion of the shaft of said other drum remains interlocked with said toothed ring.

5 6. In a hoist, a frame having end supports and a central support, a motor carried by said frame at one end thereof, shafts driven by said motor and arranged in axial alinement and journaled at their remote ends in said end supports and at their adjacent ends in said central support, coupling means within said central support for connecting said shafts for rotation together, relatively rotatable cable winding drums arranged between said end supports and said central support at the opposite sides of the latter and journaled on and supported by said axially alined shafts respectively, and driving connections between said shafts respectively and said drums for the independently rotating the latter in cable winding direction, said driving connections including reaction gears in adjacency to and at opposite sides of said central support and having hubs journaled therein, said hubs supporting bearings in which the adjacent ends of said shafts are journaled.

30 7. In a hoist, a frame having end supports and a central support, shafting journaled in said supports, relatively rotatable cable winding drums arranged between said end supports and said central support at opposite sides of the latter and journaled on and supported wholly by said shafting, and driving connections between said shafting and said drums for independently driving the latter in cable winding direction and including driving gears fixed to said shafting at opposite sides of and in adjacency to said central support and cooperating gears journaled in said central support independently of said shafting and providing intermediate supports for the latter.

35 8. In a hoist, a frame having end supports and a central support, axially alined shafts journaled in said supports, relatively rotatable cable winding drums arranged between said end supports and said central support at opposite sides of the latter and journaled on and supported wholly by said shafts, said central support having projecting circular bosses at its opposite sides, bearings supported within said bosses in which the adjacent ends of said axially alined shafts are journaled, bearings supported by said bosses externally thereof, and driving connections between said shafts respectively and said drums for independently driving the latter in cable winding direction and including reaction members journaled on said last mentioned bearings.

40 9. In a hoist, a frame, a pair of coaxial cable winding drum units mounted on said frame and each embodying drum supporting and driving means, said supporting means including a support between said drums and said driving means including driving elements for each unit having a bearing mounting in said support, and a releasable coupling between the driving elements of the two units whereby one unit may be removed axially from said supporting means without disturbing the other unit, its drive, or the bearing mounting of its driving element in said support.

45 10. In a hoist, a frame having end supports and a central support, a pair of coaxial cable winding drum units arranged between said supports and supported thereby and each having driving means, said units being supported at their remote ends by said end supports and at their 50 adjacent ends by said central support and an

7
element of the driving means of each unit having a bearing mounting in said central support, and a releasable coupling arranged within said central support for connecting the driving elements of the two units together whereby the driving means of one unit may be driven through the driving means for the other unit, and said coupling permitting removal of one unit without disturbing said other unit, its drive, or the bearing mounting of its driving element in said central support.

11. In a hoist, a frame having end supports and a central support, axially aligned shafts journaled in said supports, relatively rotatable cable winding drums arranged between said end supports and said central support at opposite sides of the latter and journaled on and wholly supported by said shafts, bearings supported by said central support in which the adjacent ends of said shafts are journaled, bearings supported by said central support externally of said shaft-bearings, and driving connections between said shafts respectively and said drums for independently driving the latter in cable winding direction, and including reaction members journaled on said last mentioned bearings.

12. In a hoist, a frame having end supports and a central support, axially aligned shafts journaled in said supports, relatively rotatable cable winding drums arranged between said end supports and said central support at opposite sides of the latter and journaled on and supported wholly by said shafts, bearings supported by said central support in which the adjacent ends of said shafts are journaled, an axially releasable coupling arranged within said central support intermediate said bearings for connecting said shafts together, bearings supported by said central support externally of said shaft-

bearings and said coupling, and driving connections between said shafts respectively and said drums independently driving the latter in cable winding direction, and including reaction members journaled on said last mentioned bearings.

13. In a hoist, a frame having end supports and a central support, shafting journaled in said supports, relatively rotatable cable winding drums arranged between said end supports and said central support at opposite sides of the latter and journaled on and supported wholly by said shafting, said central support having circular projecting bosses at its opposite sides, bearings supported within said bosses in which the central portion of said shafting is journaled, bearings supported by said bosses externally thereof, and driving connections between said shafting and said drums for independently driving the latter in cable winding direction, and including reaction members journaled on said last mentioned bearings.
